United States Patent Office.

WALTER F. JONES, OF SYRACUSE, NEW YORK.

Letters Patent No. 91,750, dated June 22, 1869.

IMPROVEMENT IN PUMPS.

The Schedule referred to in these Letters Patent and making part of the same

To all whom it may concern:

Be it known that I, WALTER F. JONES, of Syracuse, in the county of Onondaga, in the State of New York, have invented a new and improved Mode of Elevating or Forcing Water; and I do hereby declare that the following is a full and exact description thereof, reference being had to the accompanying drawings, and to the letters of reference marked thereon.

The nature of my invention consists in elevating or forcing water, by means of a plunger or shaft, tapered at the lower extremity in the form of a wedge or cone, and put in the place of an ordinary piston-rod, in a common force-pump.

To enable others skilled in the art to make and use my invention, the I will proceed to describe its construction and operation.

I construct a hollow cylinder, as shown at A in the accompanying drawing, of iron, wood, or other metal, of diameter proportionately larger than that of my plunger, which is marked B in the drawing.

At the bottom, or near the bottom, on the side of the cylinder, I insert a valve, marked C, which opens within the cylinder, in order to enable the water to fill the same when the lower point of the plunger is drawn up to the top or cap of the cylinder, which is marked D.

At the bottom edge of this cylinder, I attach an escape-pipe, marked E, of any known ordinary form, in which there is a valve, marked F, opening within the escape-pipe, to prevent the water flowing back into the main cylinder.

The top and bottom of the cylinder are made of iron plates, and firmly secured with bolts.

A hole is made through the top plate, which is marked G, of diameter the same as that of the plunger, through which the plunger is to pass into the cylinder, and penetrate nearly to its bottom.

The hollow of the cylinder is to be from one to three inches in diameter greater than that of the plunger,

and the plunger is to pass directly through the centre of this hollow, so that it may not come nearer than one or two inches (more, the better,) of the side of the cylinder.

This cylinder may be of any required strength, length, and size, and is to be wholly immersed in water.

The plunger, besides being, at its lower extremity, in a wedge or cone-form, should perfectly fill the hole in the top plate, or, at that point, be surrounded with sufficient packing to prevent the water escaping therefrom, so that when the plunger is forced down, and penetrates the water in the cylinder, the water flows into the escape-pipe.

The plunger is made of iron or other metal.

This form of plunger, first, acts upon the water on the principle of a wedge or inclined plane, and diminishes the power necessary to overcome the resistance in an ordinary force-pump; second, it displaces and forces a column of water (the size of the plunger) through the centre of the water in the cylinder, and but slightly disturbs the water at the sides. Thereby it avoids, or rather it does not produce any friction at the sides of the cylinder, which is created by a common piston-rod in an ordinary force-pump.

I am aware that pumps have been constructed (and used) on the same principle as mine, but the plunger or piston of quite a different shape.

Having thus fully described my invention,

What I claim as new, and desire to secure by Letters Patent, is—

The piston or plunger B, provided with a wedge or cone-shaped point, and used in combination with a force-pump, substantially as shown and described.

WALTER F. JONES.
